UNITED STATES PATENT OFFICE.

CHARLES H. BURBIDGE, OF NEW YORK, N. Y.

METAL DOOR CONSTRUCTION.

1,118,265.

Specification of Letters Patent. Patented Nov. 24, 1914.

Application filed August 4, 1911. Serial No. 642,420.

To all whom it may concern:

Be it known that I, CHARLES H. BURBIDGE, a citizen of the United States, and a resident of New York, county and State of New York, have invented certain new and useful Improvements in Metal Door Construction, of which the following is a full, clear, and exact specification.

This invention relates more particularly to making metallic trimmings and various classes of structural parts for buildings, cars, vessels or other purposes, and has for its object primarily to provide a form of construction wherein is employed sheet metal entirely for forming doors, sash, window frames, interior and exterior finishings, etc., in sectional parts so as to be adapted to be interlocked when assembled and the parts firmly held together without the use of bolts, screws, or like means; and to provide for permitting the doors, sash, finishings, etc., to be made either highly ornamental or plain in design as well as being very durable and practically fire-proof.

My invention further provides for a simplified construction for making metal doors or the like by which a great saving of material, time and labor is made as compared with the forms of this class of construction at present in use.

With these and other objects in view my invention will be more particularly described with reference to the accompanying drawing which forms a part of this specification, and will then be pointed out in the appended claims.

In the drawing, Figure 1 is a side elevation of one form of metal door constructed according to my invention. Fig. 2 is a section taken on the line II—II of Fig. 1. Fig. 3 is a section taken on the line III—III of Fig. 1. Fig. 4 is a section taken on the line IV—IV of Fig. 1. Fig. 5 is a section taken on the line V—V of Fig. 1. Fig. 6 is a section taken on the line VI—VI of Fig. 1. Fig. 7 is a perspective view of a form of channel bar or element adapted for use to stiffen parts of doors. Fig. 8 is a fragmentary view showing the end-plate on top of the length of the top rail and bottom rail, and Fig. 9 is a section through either the top rail or bottom rail showing the end-plate when integrally formed with the face-plates thereof.

For the purpose of setting forth one manner of putting my invention into practice I

have illustrated it in connection with a metal door, as 10, consisting of two end stiles 11 and 12, a cross-rail 13, a top rail 14, and a bottom rail 15, though it is evident that other forms of doors having, for instance, as many intermediate center stiles and rails as desired may also be constructed. Between said stiles and rails may be held panels 16 and 17 of metal, glass, or other preferred material. The end stiles 11 and 12 are alike in formation and usually the same in size. Each of the stiles 11 and 12 has two opposed face-plates or members 18 and 19 which are disposed on different relative planes, as viewed in cross-section, and at one of the lengthwise edges of said face-plates is provided an end-plate or member 20. The face-plates or members 18 and 19 and the end-plate or member 20 may be integrally formed by angularly bending a single sheet of metal, or made separately and connected together so as to provide a hollow body 21 of substantially a U-shape. At the opposite lengthwise edge of each of the face-plates 18 and 19 is an inwardly curved strip, as at 22 and 23, which is disposed in parallel arrangement with respect to the corresponding surface of each of said face-plates so as to provide therebetween spaces, as 24 and 25. Similarly to the end stiles 11 and 12 the top rail 14 and bottom rail 15 are also formed alike. As shown in cross-section, Fig. 5, each of said rails 14 and 15 has a face-plate or member 26 and disposed in spaced apart parallel relation thereto is a second face-plate or member 27. At one of the lengthwise edges of the face-plates 26 and 27 is an end-plate or member 27^a which may be formed integral with said face-plates by angularly bending a single sheet of metal so as to provide a hollow body 28 of approximately a U-shape, Fig. 9. At the lengthwise edge of each face-plate 26 and 27 opposite to the end-plate 27^a is an inwardly curved strip, as at 29 and 30, which is disposed in parallel relation with respect to the corresponding surface of each of said face-plates so as to provide spaces 31 and 32 therebetween. At the opposed crosswise ends of the top rail 14 and bottom rail 15 is provided a tongue 33 adapted to fit between and rest against the inner surfaces of the face-plates 18 and 19 of the stiles 11 and 12, respectively, when the parts of the door are assembled, and said tongue consists of two strips 34 and 35 which are formed by

reducing the cross-ends of the face-plates or members 26 and 27 of said rails.

While I have illustrated a form of door 10 in which is employed only one cross-rail 13, it is to be understood that types of doors 5 13, as indicated in cross-section Fig. 6, has a hollow body 36 formed of two spaced apart parallel arranged face-plates or members 37 and 38. The opposite lengthwise edges of each of the face-plates 37 and 38 are inwardly curved to provide strips, as 39 and 40, which are directed in parallel arrangement with relation to the corresponding surface of each of said face-plates whereby spaces 41 and 42 are provided therebetween and upon the opposed crosswise ends of each of said face-20 plates is a straight strip, as 43 and 44 Fig. 3, by which a tongue 44 is provided and which are formed by reducing the respective ends of the face-plates 37 and 38.

In order to properly hold the panels 16 25 and 17 in the door 10 each of the stiles 11 and 12, top rail 14, bottom rail 15, and cross-rail 13 are provided with a panel bracket 45. All of the panel brackets 45 are similarly fashioned each having two parallel plates, 30 46 and 47, which are spaced apart at a sufficient distance to rest against the inwardly curved strips of each face-plate of the various stiles and rail when positioned therebetween. Each of the corresponding ends of 35 the parallel plates 46 and 47 are curved so as to form a substantially convex body 48 in the apex of which is formed a groove 49 for reception of the ends of the door panels 16 and 17. When the various above described parts of the stiles 11 and 12, top rail 14, bottom rail 15, and cross-rail 13 are assembled I provide a locking element 50 40 adapted to securely hold said parts in locked engagement and the use of which also serves 45 to strengthen the structural parts of the door as well as permitting the use of spot-welding for connecting said parts, thus dispensing with the use of bolts, screws, or the like.

Each locking element or key 50 has a 50 bridging-plate or member 51 and upon the lengthwise edges of said bridging-plate is provided a substantially U-shaped gripping member, as 52 and 53, each of which are preferably formed by angularly bending opposite portions of a strip of metal lengthwise thereof in a direction to form two similarly disposed arms and recurving each arm, as 54, so as to form a second arm spaced in parallel relation with each of the first 55 arms whereby a space, as 55, may be provided therebetween.

To close the open opposed ends of the stiles 11 and 12 between the face-plates at the upper edges of the top rail 14 and bottom rail 15 may be arranged a channel-bar 60

or stiffening element 56, Fig. 7. The channel-bar 56 has a substantially U-shaped body 57, comprising a cross-plate 58 and upon the edges thereof are formed similarly disposed flanges or projecting plates 59 and 60. One of the channel-bars 56 is suitably connected between the face plates adjacent to the upper edge of the top rail 14 and adjacent to the lower edge of the bottom rail 15, and a part of each of said channel bars 75 is arranged to extend from the rails so as to be inserted within the hollow body at the ends of each of the stiles 11 and 12, it being understood that a portion of the ends of each of the inturned strips of the stiles may 80 be cut away and the locking elements 54 made somewhat shorter in length than the stiles whereby a space may be provided at the ends of the stiles so as to accommodate therein the ends of the stiffening elements 56. 85 A portion of the flanges 59 and 60 of the part adapted to be inserted into the stiles 11 and 12 are reduced, as at 61 and 62, and a substantially rectangular cap, as 63, is provided to snugly fit upon said reduced portions. In some doors the top edge of the rail 14 and the underneath edge of the bottom rail 15 are open when the parts thereof are assembled, and in such forms of doors the channel-bar of stiffening element 56 is 90 formed of sufficient length to extend entirely through said rails and into the body at the ends of the stiles 11 and 12. For the purpose of then closing the open top and bottom edges of the door the upper portions of the flanges 59 and 60 are reduced the entire length thereof as indicated by dotted lines 64, and a cap, as 63, of sufficient length to inclose the entire open edges of the door is fitted upon the reduced portions of said 100 flanges.

In the foregoing description I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope 110 thereof.

Having thus described my invention, I claim as new and desire to secure by Letters Patent:—

1. In a metal door construction, the combination of stiles and rails adapted to retain panels, said stiles and rails being substantially U-shaped in cross-section, and each of these parts having the edges reflexively bent inwardly, whereby a channel 120 is formed, extending flanges on the ends of each rail, adapted to be inserted endwise in the channels of the stiles, and panel-brackets, each having a groove adapted to receive the edge of a panel, and having two 125

straight flanges adapted to fit edgewise in the channel of the adjacent stile or rail, and a key-member substantially U-shaped in cross section, and having reflexively bent 5 straight flanges adapted to interlock with the reflexively bent edges of the stiles and rails, said key-members to be put in place in the channel, and the panel-bracket inserted edgewise thereafter, said flanges of 10 the rails also being inserted after the key is positioned, substantially as and for the purposes set forth.

2. In a metal door construction, the combination with two stiles, a top rail, and a 15 bottom rail substantially U-shaped in cross-section, the edges of these parts being reflexively bent inwardly, whereby a channel is formed, extended bent flanges on the ends of each rail adapted to be inserted endwise 20 in the channels of the adjacent stiles, a plurality of panel brackets, each having two reflexively bent extended straight flanges adapted to fit edgewise in the channel of the adjacent stile or rail, and a plurality of 25 key-members, each being U-shaped in cross-section and having extended straight flanges reflexively bent, said key-members being adapted to be inserted in the channels of the stiles and rails, and between the extended 30 straight flanges of the panel-brackets, the flanges of the rails and stiles and the flanges of the panel-brackets being interlocked with the reflexively bent flanges of the key members, said key-members being 35 first put in place in the channel, the flanges of the panel brackets, and the flanges of the rails being inserted thereafter, substantially as and for the purposes set forth.

3. In a metal door construction having 40 stiles, a top rail, and a bottom rail of the character described, a middle rail comprising two side plates, each having a bent end portion or flange adapted to be inserted endwise in the adjacent channel in the stile 45 of the door, each of said side plates having its edges reflexively bent inwardly where-

by an open channel is formed at the top and bottom of the rail, said channel being adapted to receive mating parts comprising panel brackets, said panel brackets, having 50 a groove to receive the edge of a panel and also having extending straight flanges adapted to be inserted edgewise between the flanges of the side plates of the rail, and key members substantially U-shaped in 55 cross-section, and having reflexively bent straight flanges, said key-members being adapted to be inserted between the flanges of the panel-brackets, the flanges thereof interlocking with the reflexively bent 60 flange of the side plates, said key-members being first put in position, and the panel brackets being inserted edgewise thereafter, substantially as and for the purposes set forth.

4. In a metal door construction of the character described, the combination with a bent metal frame substantially U-shaped in cross-section, and having two side plates connected by an edge plate, the edge of 70 said side plates being reflexively bent inwardly whereby a channel is formed longitudinally of the inner edge portion of the frame, of a panel bracket having a substantially U-shaped channel to receive the 75 edge of a panel, reflexively bent extending straight flanges adapted to fit edgewise within the channel of the frame, and substantially U-shaped key-members having reflexively bent flanges interlocking with the 80 reflexively bent flanges of the side plates of the frame, said key-members being first put in place in the channel, and the panel-bracket being inserted edgewise thereafter, substantially as and for the purposes set 85 forth.

This specification signed and witnessed this second day of August A. D. 1911.
